UNITED STATES PATENT OFFICE.

LOUIS KYSER AND ALFRED C. REX, OF PHILADELPHIA, PENNSYLVANIA.

DESIGN FOR A TOY MONEY-BOX.

SPECIFICATION forming part of Design No. 12,860, dated April 11, 1882.

Application filed February 13, 1882. Term of patent 3½ years.

To all whom it may concern:

Be it known that we, LOUIS KYSER and ALFRED C. REX, both of the city and county of Philadelphia, and State of Pennsylvania, have 5 invented an Improvement in Designs for Toy Money-Boxes, of which the following is a specification.

Our invention relates to designs for toy money-boxes; and it consists in forming the 10 same into the representation of a church in front, having two towers arranged on either side of a center piece, having a Gothic top and the representation of a door, the back having windows, but no towers, the top of said box 15 being formed to represent three roofs arranged parallel to each other or one roof having three ridges, and in other details, all of which are fully set out in the following specification and shown in the accompanying drawings, which 20 form part thereof.

The object of this invention is the design for a toy money-box which shall be both ornamental and cheap to construct.

In the drawings, Figure 1 is a front elevation of our improved design for toy money-box. 25 Fig. 2 is a back elevation of same. Fig. 3 is a perspective view of the general shape, and Fig. 4 is a plan.

The body consists in front of the center piece, 30 A, having a Gothic top, L, a representation of a window, D, and a door, C, having steps E. On each side of said piece A is a tower, B, having battlements N on top and windows G and H. The base of the body is provided with 35 an ornamentation, F, extending all around. The back of the box is composed of a similar design to the front, with the exception that the towers are cut off and Gothic tops K substituted therefor, and the door C is changed 40 into a double window or two windows, I, with

a scroll, J, below them. The top of the box consists of the three-ridged roofs K L K, having the slot M for the deposition of money in the groove corresponding to the junction of two of said roofs. The box is made in two parts, as 45 shown in Fig. 3, and is held together by a bolt with a round head, which forms the windows D. The body is made to represent stone-work or masonry.

Having now described our invention, what 50 we claim as new, and desire to secure by Letters Patent, is—

1. The design for a toy money-box, which consists of the body of general rectangular shape, having two towers and a center piece in 55 front, and a three-ridged roof, substantially as and for the purpose specified.

2. The design for a toy money-box, which consists of the body of general rectangular shape, having its front made with two towers, 60 and a center piece provided with a Gothic top and a door, substantially as and for the purpose specified.

3. The design for a toy money-box, which consists of the body of general rectangular 65 shape, having its front made with two towers, and a center piece provided with a Gothic top and a door, its back made of a piece with three Gothic tops and provided with windows, and the body being covered with a three-ridged 70 roof corresponding to the three Gothic tops, substantially as and for the purpose specified.

In testimony of which invention we hereunto set our hands.

LOUIS KYSER.
ALFRED C. REX.
